UNITED STATES PATENT OFFICE.

AARON McELVEEN, OF STILSON, GEORGIA.

PUZZLE.

1,270,181.

Specification of Letters Patent. Patented June 18, 1918.

Application filed November 20, 1917. Serial No. 203,000.

To all whom it may concern:

Be it known that I, AARON McELVEEN, a citizen of the United States, residing at Stilson, in the county of Bulloch and State of Georgia, have invented certain new and useful Improvements in Puzzles, of which the following is a specification.

My invention relates to puzzles.

My object is to provide a puzzle put together in such a way that it at once appears an utter impossibility to have assembled the parts in the way in which they appear, or to disassemble them after they are thus assembled.

15 A further object is to heighten the effect of the delusion by making the different parts of the device out of pieces of material strikingly different from each other in appearance, so as to instantly preclude the idea 20 (liable to present itself as a solution of the problem) that the puzzle may have been cut out in a skilful manner from a single piece of material, and that its parts have therefore never really been separated from each 25 other.

Another object is to provide a puzzle formed of few and simple parts easily and cheaply made, and which when assembled seem to have been put together so easily that 30 the device while defying solution tantalizes one by its manifest simplicity.

An important feature of the invention consists in a major member having an opening therein in which opening is received, or 35 is to be received, a plurality of minor pieces having cut-away portions between their ends, with the opening in the major member only large enough to simultaneously hold all the minor pieces at their intermediate cut-away 40 portions. Hence, the puzzle presents apparently the impossible task of passing through an opening of a given size, a piece of material considerably larger than the opening.

45 The novelty of the invention consists in the construction and arrangement of the several parts considered in connection with the nature of the material from which the parts are formed, as will be hereinafter described 50 and claimed, reference being had to the accompanying drawings, in which:

Figure 1 is a perspective view of one form of my puzzle.

55 Fig. 2 is a vertical longitudinal section of Fig. 1.

Fig. 3 is a perspective of one of the minor members of my device, and;

Fig. 4 is a top plan view of a slightly modified form of the device showing the major member provided with four minor 60 members instead of only two, as shown in Figs. 1 and 2.

The secret of the puzzle resides in the fact that at least one (if not more) of its minor or notched members is formed of elastic ma- 65 terial, preferably wood.

It is not generally known, or if known not generally considered, that certain kinds of wood—and to some degree, practically every kind of wood—can be placed in a vise 70 or other suitable apparatus and greatly compressed in size or bulk, especially when dry; and that when compressed they will not immediately resume their original size and shape, but will have a tendency to retain 75 their compressed form; but that when placed in water they will readily expand to their original size and shape.

With this explanation it is easily seen how 80 the puzzle is solved.

Referring further to the drawings, the numeral 1 indicates the major member of my puzzle which may be made in any desired shape—rectangular, square, round, heart-shaped, etc.—and is provided preferably at 85 its center with an opening 2. The minor members 3 and 4 of the device are cut-away between their ends to form the notches 5. The upper and lower ends 3^a and 4^a respectively of these minor members are prefer- 90 ably of a shape and size to loosely fit the opening 2 of the major member, so that any one of said ends approximately fills said opening as it passes through it.

Each of the minor members 3 and 4 is 95 reduced about one half in cross sectional area at its notched portion, so that when the ends 3^a and 4^a have been passed through the opening 2 of the major member, the reduced portions 3^b and 4^b of the two notched members will be easily received and held in said opening 2, as illustrated in Figs. 1 and 2.

In Fig. 4 I have shown the major member 1 provided with a rectangular opening 2^a, 105 and the notched blocks are made small enough for four of them, numbered 6, 7, 8 and 9, to be received into this opening, instead of two blocks as in Figs. 1 and 2. These blocks 6, 7, 8, and 9 are preferably 110

square in cross section (at their ends) and are cut away about one half at their notched portions between their ends, just as are the blocks 3 and 4 in the other figures; so that 5 when arranged as in Fig. 4 their reduced portions loosely fill the opening 2^a. This opening is about three times as long as it is wide in order for the blocks to approximately fill it with their reduced portions 10 when formed and arranged as shown and described.

If it is desired to form one of these puzzles with only three notched blocks, either the block 6 or 8 may be omitted (referring 15 to Fig. 4) together with the portion of the opening 2^a into which the reduced portion of the omitted block is now received.

It is not deemed necessary to point out other manifest changes which might be: 20 made in the size, shape, and number of the blocks, shape of the opening into which they would be received, etc.

In passing the notched blocks 3 and 4 through the opening 2 in order to assemble 25 or disassemble the parts of the puzzle, it is simply necessary to compress one or more (as may be preferred) of the projecting ends 3^a and 4^a of the blocks, sufficiently to permit the same to pass through the opening 2. This can usually best be done by 30 means of a vise. If a projecting end of each of the blocks be compressed, it is manifest that each will only have to be compressed half as much as if only one block 35 is compressed, and in that case both blocks can be passed through the opening 2 at once. On the other hand, if only one block is compressed, the other block is placed in position in the opening first, and then the compressed block is entered in position. After 40 the blocks 2 and 3 have been entered in proper position in the opening 2, the compressed portion, or portions as the case may be, is placed in water till it assumes its 45 original size and shape.

Inasmuch as well known means has been devised for cutting a single piece of wood into two or more pieces interlocked or otherwise related to each other in a way that 50 appears impossible to have been effected—as, for instance, a wooden bottle with a ball inside it larger than the neck of the bottle—Some persons will at first sight conclude that this puzzle belongs to that class 55 of devices; and it is best that their minds should be forestalled in the outset against any such erroneous opinion, in order that the puzzle may make its strongest possible appeal to them as something apparently impossible that has yet actually been done. From the foregoing description it will be seen that if but one of the notched blocks 60 of my device be formed of soft resilient wood, such for instance as white pine, the 65 other parts may be formed of non-resilient

material such as metal, and each piece of a different kind of metal if so desired. However it is thought that the real secret of the puzzle will remain more completely hidden if the notched blocks, at least, are all formed 70 of wood, since if only one soft wooden block were used with a number of metal blocks some active minds would quickly conclude, since metal had been largely employed in the construction of the device and was manifestly the most desirable material to be used 75 if possible, that that one block of soft wood had been used from necessity and not from choice; and hence they would at once suspect that the solution of the puzzle lay in 80 that piece of wood.

In view of the foregoing, it is thought that the best possible effect can be produced and the secret of the puzzle kept most fully hidden by forming all the notched blocks 85 of wood, and having each block formed of a different kind of wood from the blocks adjacent to it, and each different kind of wood being of a strikingly different color to give as great a contrast as possible in colors. No 90 artificially colored blocks should be used since the use of artificial colors would tend to defeat the very object sought in providing blocks having contrasting colors.

Of course, at least one block should always preferably be of some soft wood such as white pine or bay wood since soft woods are much more easily compressed, and are less liable to become split or otherwise damaged in being compressed. 100

In Fig. 4 I have indicated the blocks 6 and 8 (which are separated from each other) as formed of white wood such as white pine; the block 7 of red wood; and the block 9 of black wood, as ebony. In Figs. 1 and 2 I 105 have indicated the block 3 as formed of red wood, and the block 4 of white wood—white pine.

Nice mechanical workmanship may be displayed by making the major member 1 of 110 my device out of metal, but in that case care should be exercised to select a metal that will not easily rust when the device is placed in the water to reexpand the compressed blocks. 115

Having thus disclosed my invention, what I claim as new and desire to protect by Letters Patent is:—

1. A device of the character described, comprising a major member having an opening; and a plurality of minor members designed to be received thereinto, said minor members having reduced sections between their ends and being formed of materials differing from each other in natural appearance, one at least of said minor members being formed of resilient material, the opening in the major member being of a size to simultaneously receive the reduced portions only of the minor members. 120 125 130

2. A device of the character described, comprising a major member having an opening; and a plurality of minor members adapted to be received thereinto, said minor members 5 having reduced sections between their ends and being formed of materials whose natural colors contrast with each other, one at least of said members being formed of resilient material, the opening of the major member 10 being of a size to simultaneously receive the reduced portions only of the minor members.
3. A device of the character described, comprising a major member having a central 15 opening extending transversely therethrough and a plurality of elongated minor members

having reduced sections midway between their ends and designed to be received at their reduced portions into said transverse opening of the major member, said minor 20 members being formed of resilient woods and made similar to each other in shape and size but contrasting with each other in their natural colors, the opening in the major member being of a size to simultaneously 25 receive the reduced portions only of the minor members.

In testimony whereof I affix my signature.
AARON McELVEEN.
